PAGE-END INDICATOR

Martin M. Price, Orange, N. J.

Application February 10, 1932. Serial No. 592,035

16 Claims. (Cl. 197—189)

My present invention relates to indicators, and more particularly to devices of the general character specified which may be used in conjunction with typewriting machines and which are adapted to warn the operator of the approach of the end or bottom of a page.

It is one of the main objects of the present invention to provide what may be termed a page-end indicator which is exceedingly simple in construction, easy and economical to fabricate and assemble, and which performs the intended functions in an admirable manner.

I am aware of the fact that page-end indicators are not broadly new, but I have found that they are for the most part cumbersome, complicated and therefore expensive. Furthermore, all of the page-end indicators of which I am aware are designed to constitute an integral part of the typewriter, whereas the present invention is intended to be an attachment which may be very readily and speedily secured to any existing typewriter.

In the accompanying specification I shall describe, and in the annexed drawing show, an illustrative embodiment of the page-end indicators of the present invention. It is, however, to be clearly understood that I do not wish to be limited to the exact construction herein shown and described for purposes of illustration only.

30 In the accompanying drawing:

Fig. 1 is a side elevational view of the aforesaid illustrative embodiment of the present invention, the same being partly in section to show the internal construction; and

35 Fig. 2 is a front elevational view of the same.

Referring now more in detail to the aforesaid illustrative embodiment of the page-end indicators of the present invention, and with particular reference to the drawing illustrating the same, the numeral 10 generally designates the carriage of a conventional typewriter, which carriage carries the platen or roller 11 with which cooperates the paper guide 12, the platen and paper guide being adapted to accommodate between the same 40 a sheet of paper P.

Secured to any desired part of the carriage 10, to the rear of the platen 11, by means of screws 13, is a triangular plate 14 to which in turn is fixed, by means of screws 15, a vertical support 45 bar 16. The bar 16 is provided, on the front face thereof, with rack teeth 17, and adapted to slide vertically over the bar 16 is a tubular guide 18, of square cross section, to fit the bar, formed on a rectangular casing 19. The lower wall of 50 the casing 19 is provided with a downwardly di-

rected lug 20 in which there is rotatably mounted a pintle 21 having fixed at the inner end thereof a pawl 22 adapted to cooperate with the teeth 17 of the bar 16. The pawl 22 is normally maintained in engagement with the teeth 17 by means 60 of a flat spring 23, one end of which is fixed to the pawl and the other end of which urges against the under surface of the lower wall of the casing 19. In order to disengage the pawl 22 from the teeth 17 of the bar 16, I provide the outer end 65 of the pintle 21 with an operating member 24. Thus, the casing may be moved freely upwardly but cannot be moved downwardly unless the pawl 22 is first disengaged from the teeth 17 by means 70 of the operating member 24. The purpose of this arrangement will become apparent as the description progresses.

Fixed to the top wall of the casing, within the same, is a pair of U-shaped supporting brackets 25 and 26, the lower ends of the arms of said 75 brackets being adapted to rotatably support a shaft 27. Fixed upon the shaft 27 intermediate the arms of the inner bracket 25 is a solid drum 28 about which is coiled a spring 29, the inner end 30 of the spring being fixed to the drum 28 80 and the outer end 31 of such spring being fixed at 32 to the rear wall of the casing 19.

Fixed upon the shaft 27 intermediate the arms of the inner and outer brackets 25 and 26 is a pair of reels 33, each of which is adapted to 85 carry a coil of wire 34 of a certain definite length, as will hereinafter be more fully explained. The coils of wire 34 constitute supports which pass downwardly out of the casing 19 through guides 35, the lower ends 36 of such wire supports being 90 looped to support a clip generally designated by reference character 37. The clip 37 consists of the gripping jaws 38 normally urged together by means of a spring 39, the jaws extending upwardly beyond the spring to form operating handles 40. 95 The wire supports 34 are connected adjacent the top of the clip 37 by a cross bar 41.

The length of the wires 34 is such that when the casing 19 is supported in its lowermost position on the bar 16, the clip 37 will become disengaged from the lower edge of the paper P, as will hereinafter be more fully understood, when almost all of the sheet of paper P has passed almost entirely about the platen 11; in other words, when the end of the page is about to be 100 reached by the operator. Thus, by regulating the height of the casing 19 on the bar 16, the clip 37 can be made to disengage from the paper P when the paper has passed predetermined distances through the machine. By this means, the 110

typist can in advance, knowing how much written matter he desires on any particular sheet of paper, cause a signal to be given when the paper has passed a predetermined distance through the machine. The signal which I prefer to employ is as follows:

Fixed to the undersurface of the lower wall of the casing 19, adjacent the front edge thereof, is a bracket 42 which is adapted to pivotally carry a tripping lever 43, the inner end 44 of which is positioned in the path of the cross bar 41 and the outer end 45 of which carries a clapper 46 adapted to cooperate with a bell 47 carried at 48 by the front wall of the casing 19.

This completes the description of the aforesaid illustrative embodiment of the page-end indicators of the present invention. It will be noted from such description that the same are simple in construction, easy and economical to fabricate and assemble, and admirably adapted to perform the intended functions.

It is believed that the operation of the aforesaid illustrative embodiment of the present invention is clearly apparent from the foregoing description, but for purposes of clarity the same may be briefly summarized as follows:

After the typist has inserted the sheet of paper P in the machine in the usual manner, he approximates how much space on the sheet of paper will be necessary to include all of the matter to be written, and by employing a scale 49 which may be carried by the bar 16, slides the casing 19 over the bar 16 until the pawl 22 is engaged with the tooth 17 corresponding to the space that he has determined will be necessary. The clip 37 is then engaged with what will be the lower edge of the sheet P, this being done by pressing together the operating handles 40 and inserting the sheet P intermediate the gripping jaws 38 and thereafter releasing the handles 40.

The typewriter is now operated in the usual manner and as soon as the paper has passed through the machine the distance to which the device has been set, the wire supports 34 will become taut, having been unrolled their entire length, thus preventing the clip 37 from further following the sheet P. Obviously, during the unrolling of the wire supports 34, the shaft 27 has been rotated so as to wind up the spring 29. Any continued movement of the paper P through the machine causes the clip 37 to become disengaged from the paper and the spring 29 will be free to rotate the shaft 27 in a direction opposite to that in which it was rotated during the winding up of the spring. This will cause the clip to move upwardly toward the casing and the cross bar 41 to come in contact with the inner end 44 of the tripping lever 43. The latter will be pivoted in the bracket 42 to cause the clapper 46 to ring the bell 47, thus giving the operator an audible signal that the paper has passed through the machine the predetermined distance to which the device had been set.

Obviously, if the operator determines that the amount of written matter which he is desirous of typewriting will cover more than one sheet of paper, the device is set so as to permit the paper to pass almost its full length through the machine before the clip 37 will become disengaged from the paper.

This completes the description of the mode of use and operation of the page-end indicating devices of the present invention.

As before stated, it is believed that this invention includes a page-end indicator which is ex-

ceedingly simple in construction, very easy and economical to fabricate and assemble, and adapted to perform its intended functions in a very efficient manner.

Other superiorities and advantages of the means of the present invention will readily occur to those skilled in the art to which the present invention relates.

What I claim as my invention is:

1. An attachment for typewriters comprising a support, a casing adjustable along said support, an audible signal, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, means for tensioning said reels during the unwinding, and means for adjusting the height of said casing along said support whereby said gripping means disengages the sheet of paper after the latter has passed a predetermined distance through the machine, permitting said tensioning means to retract said wires and the gripping means carried thereby to operate said audible signal.

2. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, means for tensioning said reels during the unwinding, and means for adjusting the height of said casing along said support whereby said gripping means disengages the sheet of paper after the latter has passed a predetermined distance through the machine, permitting said tensioning means to retract said wires and the gripping means carried thereby to operate said signal-operating means.

3. An attachment for typewriters comprising a support, a casing adjustable along said support, an audible signal, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, tripping mechanism carried by said wires adjacent said gripping means, means for tensioning said reels during the unwinding, and means for adjusting the height of said casing along said support whereby said gripping means disengages the sheet of paper after the latter has passed a predetermined distance through the machine, permitting said tensioning means to retract said wires, said tripping mechanism and the gripping means carried thereby to operate said audible signal.

4. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means.

- thereof fixed to said gripping means, said wires unwinding as the sheet of paper passes through the machine, tripping mechanism carried by said wires adjacent said gripping means, means for 5 tensioning said reels during the unwinding, and means for adjusting the height of said casing along said support whereby said gripping means disengages the sheet of paper after the latter has passed a predetermined distance through the machine, permitting said tensioning means to retract said wires, said tripping mechanism and the gripping means carried thereby to operate said audible signal. 80
5. An attachment for typewriters comprising a support, a casing adjustable along said support, an audible signal, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, a coiled spring having its inner end rigidly associated with said reels and its outer end fixed to said casing for tensioning said reels during the unwinding, and means for adjusting the height of said casing along said support whereby said gripping means disengages the sheet of paper after the latter has passed a predetermined distance through the machine, permitting said tensioning means to retract said wires, said tripping mechanism and the gripping means carried thereby to 95 operate said signal-operating means. 90
- 25 6. An attachment for typewriters comprising a support, a casing adjustable along said support, an audible signal, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, means for tensioning said reels during the unwinding, and manually operable means for adjusting the height of said casing along said support whereby said gripping means disengages the sheet of paper after the latter has passed a predetermined distance through the machine, permitting said tensioning means to retract said wires and the gripping means carried thereby to operate said audible signal. 100 105
- 30 7. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, a coiled spring having its inner end rigidly associated with said reels and its outer end fixed to said casing for tensioning said reels during the unwinding, and means for adjusting the height of said casing along said support whereby said gripping means disengages the sheet of paper after the latter has passed a predetermined distance through the machine, permitting said tensioning means to retract said wires and the gripping means carried thereby to operate said audible signal. 110 115
- 45 8. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, means for tensioning said reels during the unwinding, and manually operable means for adjusting the height of said casing along said support whereby said gripping means disengages the sheet of paper after the latter has passed a predetermined distance through the machine, permitting said tensioning means to retract said wires and the gripping means carried thereby to operate said signal-operating means. 120 125
- 50 9. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, means for tensioning said reels during the unwinding, and manually operable means for adjusting the height of said casing along said support whereby said gripping means disengages the sheet of paper after the latter has passed a predetermined distance through the machine, permitting said tensioning means to retract said wires and the gripping means carried thereby to operate said signal-operating means. 130 135
- 55 10. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, means for tensioning said reels during the unwinding, and manually operable means for adjusting the height of said casing along said support whereby said gripping means disengages the sheet of paper after the latter has passed a predetermined distance through the machine, permitting said tensioning means to retract said wires and the gripping means carried thereby to operate said signal-operating means. 140 145
- 60 11. An attachment for typewriters comprising a support, a casing adjustable along said support, an audible signal, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, tripping mechanism carried by said wires adjacent said 150
- 65 70 75 80 85 90 95 100 105 110 115 120 125 130 135 140 145 150

gripping means, means for tensioning said reels during the unwinding, and manually operable means for adjusting the height of said casing along said support whereby said gripping means 5 disengages the sheet of paper after the latter has passed a predetermined distance through the machine, permitting said tensioning means to retract said wires, said tripping mechanism and the gripping means carried thereby to operate 10 said audible signal.

12. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, tripping mechanism carried by said wires adjacent said gripping means, means for tensioning said reels during the unwinding, and manually operable means for adjusting the height of said casing along said support whereby said gripping means disengages the sheet of paper after the latter has passed a predetermined distance through the machine, permitting said tensioning means to retract said wires, said tripping mechanism and the gripping means carried thereby to operate said signal-operating means.

13. An attachment for typewriters comprising a support, a casing adjustable along said support, an audible signal, a pair of reels rotatably mounted in said casing, means to grip the lower edge of a sheet of paper passing through the typewriter, a coil of wire wound about each of said reels having the inner ends thereof fixed to said 35 reels and the outer ends thereof fixed to said gripping means, said wires unwinding as the sheet of paper passes through the machine, a coiled spring having its inner end rigidly associated with said reels and its outer end fixed to 40 said casing for tensioning said reels during the unwinding, and manually operable means for adjusting the height of said casing along said support whereby said gripping means disengages 45 the sheet of paper after the latter has passed a predetermined distance through the machine, permitting said tensioning means to retract said 50 wires and the gripping means carried thereby to operate said audible signal.

53 14. An attachment for typewriters comprising
a support, a casing adjustable along said sup-
port, an audible signal, signal-operating means,
a pair of reels rotatably mounted in said cas-
ing, means to grip the lower edge of a sheet of
paper passing through the typewriter, a coil of
wire wound about each of said reels having the
inner ends thereof fixed to said reels and the
outer ends thereof fixed to said gripping means.

said wires unwinding as the sheet of paper passes through the machine, a coiled spring having its inner end rigidly associated with said reels and its outer end fixed to said casing for tensioning said reels during the unwinding, and manually 80
operable means for adjusting the height of said

operable means for adjusting the height of said casing along said support whereby said gripping means carried thereby to operate said signal-latter has passed a predetermined distance through the machine, permitting said tensioning means to retract said wires and the gripping means carried thereby to operate said signal-operating means.

15. An attachment for typewriters comprising a support, a casing adjustable along said support, an audible signal, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, said wires unwinding as the sheet of paper passes through the machine, tripping mechanism carried by said wires adjacent said gripping means, a coiled spring having its inner end rigidly associated with said reels and its outer end fixed to said casing for tensioning said reels during the unwinding, and manually operable means for adjusting the height of said casing along said support whereby said gripping means disengages the sheet of paper after the latter has passed a predetermined distance through the machine, permitting said tensioning means to retract said wires, said tripping mechanism and the gripping means carried thereby to operate said audible signal. 110

16. An attachment for typewriters comprising a support, a casing adjustable along said support, an audible signal, signal-operating means, a pair of reels rotatably mounted in said casing, means to grip the lower edge of a sheet of paper passing through the typewriter, a coil of wire wound about each of said reels having the inner ends thereof fixed to said reels and the outer ends thereof fixed to said gripping means, 115 said wires unwinding as the sheet of paper passes through the machine, tripping mechanism carried by said wires adjacent said gripping means, a coiled spring having its inner end rigidly associated with said reels and its outer end fixed 120 to said casing for tensioning said reels during the unwinding, and manually operable means for adjusting the height of said casing along said support whereby said gripping means disengages the sheet of paper after the latter has passed 130 a predetermined distance through the machine, permitting said tensioning means to retract said wires, said tripping mechanism and the gripping means carried thereby to operate said signal-operating means. 135
